UNITED STATES PATENT OFFICE.

ISAAC F. WILLEY, OF PHILADELPHIA, PENNSYLVANIA.

QUILL AND HOUSING FOR MOISTURE-EXTRACTORS FOR DRYING CLOTHES.

1,252,214.

Specification of Letters Patent.

Patented Jan. 1, 1918.

Application filed July 27, 1916. Serial No. 111,569.

To all whom it may concern:

Be it known that I, ISAAC F. WILLEY, a citizen of the United States, residing in the city and county of Philadelphia, State of Pennsylvania, have invented a new and useful Quill and Housing for Moisture-Extractors for Drying Clothes, of which the following is a specification.

My invention relates to a novel construction of quill and housing for motor driven extractors or clothes-drying devices, of the class in which the basket is located at the upper portion of the machine and driven or rotated from underneath, preferably by means of an electric motor the armature of which acts as a spindle for the basket and the motor case of which is hung at the top and as heretofore constructed free to vibrate to a greater extent than desirable.

As heretofore constructed machines of this character have possessed certain disadvantages which it is the object of my invention, generally stated, to overcome by a simplification of parts and the elimination of certain of them which have been found unnecessary.

The invention comprehends a new and useful construction of the elements which support and maintain the revolute spindle of the extractor and effect its maintenance within a quill which is itself supported by and within a casing in the base of the extractor, to the end that the vibration of the motor and basket may be reduced to a minimum and the supporting elements may be so formed and assembled as to be easily disconnected and taken apart to admit of replacement or repairs.

In carrying out my objects, the quill or flexible bearing in which the spindle runs, which is made preferably of copper or bronze, is of such length and weight as effectively to withstand the strain to which it is subjected, and as in the old practice, is provided with two case-hardened convex and oppositely disposed buttons for the spindle to run on. It is moreover convex-ended and mounted within a concave casing, being retained by a gland which compresses a gasket on an external flange which it is formed with and which fits within the casing, which latter is secured to the base of the machine.

My invention further consists of a novel construction of quill or flexible bearing, the various elements of which can be readily assembled and dismantled without necessitating the employment of skilled labor, and

which will be found to be sufficient and reliable under all conditions and when once installed to require a minimum amount of attention from the operator.

For the purpose of illustrating my invention, I have shown in the accompanying drawings a certain type and embodiment of it which is at present preferred by me because in practice it has given satisfactory and reliable results.

It is to be understood, however, that the various instrumentalities of which my invention is shown as embodied can be variously arranged and organized and that my invention is not therefore limited to the precise arrangement and organization of the instrumentalities which are typified in the constructions shown in the accompanying drawings and hereinafter described.

Figure 1 represents a perspective view of a novel moisture extractor adapted for drying clothes, embodying my invention.

Fig. 2 represents a vertical section through the center of Fig. 1, the motor parts being shown in elevation.

Fig. 3 represents a plan view of the base or lower portion of the extractor.

Fig. 4 represents on an enlarged scale, a vertical section on the line 4-4 of Fig. 3.

Fig. 5 represents a sectional detail of a modification for a pulley drive for the quill.

Fig. 6 represents a sectional elevation of another embodiment of my invention.

Similar numerals of reference indicate corresponding parts in the figures.

Referring to the drawings:

1 designates my novel construction of moisture extractor or clothes-drying device as an entirety, which comprises a base portion 2, adapted to support a housing 3, which incloses or contains a revolute basket 4, which may be made of copper or other wire, preferably heavily tinned, and if desired protected by heavy steel bands, as will be understood from Fig. 2. The basket is provided with a cover or lid 24, to retain the contained clothes when the basket is rotated at a high speed.

The basket and its adjuncts may be constructed in any usual manner and as the assembling and mounting of them is well understood by those skilled in the art, no further description of them is necessary.

My invention relating more particularly to my novel construction of quill and housing in which the motor spindle runs; a pre-

ferred construction of them is the following:—

5 designates an electric motor of any preferred type having its case hung at the top so that it is free to vibrate, the motor being provided with a spindle 6, which carries an armature of the usual construction. The basket 4 being secured to the upper portion of the spindle, the spindle and basket rotate in unison.

10 7 designates a quill or journal bearing, the base or lower extremity of which is convex, as indicated at 8, to conform to the concavity 9 of the box or casing 10, within which is supported and collocated the base 8 of said journal bearing 7. The base portion 8 of said quill 7 is extended radially inward as a projecting ledge or shoulder 11 upon which rests the under side of a flanged button 12, the upper or top portion of which is convexed, as indicated at 13, and the lower or body portion 14 of which is seated in an opening 14* in the bottom of the quill 7, so as to fit snugly therein. The lower portion of the 20 spindle has secured thereto in any suitable manner a spindle button 15, the convex bottom portion of which centers and rests upon the convex top portion 13 of the lower button 12, with the result that the friction between 25 the two convex buttons is reduced to a minimum.

The quill 7 is furthermore provided with an outwardly extending lateral flange 17, which serves as a basal support for a rubber 30 gasket, cushion or spring 18, contained within the upwardly extending walls 10* of the box or casing 10, and held in position with respect to the flange 17 and the upper walls 10* of said box 10 by means of a gland or 35 nut 19, with the result not only that the gasket and quill are properly retained within the casing 10 but also that at the same time there is provided means for easing the vibration caused by the rotation of the spindle 6 and its adjuncts when the spindle is rotated at high speed.

To provide for easy assemblage and dismantling of the casing, quill and adjuncts, I provide the casing with a radially outwardly 40 extending basal flange 20, which is adapted to be bolted or otherwise secured to an inwardly projecting flange 21 of the base 2 of the extractor by means of bolts or other fastening devices 22, which in the construction 45 of Figs. 1 and 2, I have shown as being in screw-threaded engagement with the base 2, so that the base and casing 10 are firmly clamped together, while in the construction shown in Fig. 4 I have shown them reversed 50 and threaded into the flange 21.

The lower portion of the spindle 6 is provided with longitudinally extending external oil or grease grooves 23, which receive and distribute around the spindle a lubricant introduced through the inlet tube 23*.

When an electric motor, as shown in Figs. 1 and 2, is employed, I provide a rheostat or controller 25 of any usual and conventional type, whereby any necessity for a mechanical brake is dispensed with, since the controller in practice has three points,—one to start, one to stop and one to throw off the current.

If the extractor is driven by a belt, as contra-distinguished from a motor, the modified construction seen in Fig. 5 may be 75 employed, and the upper portion of the quill 7 be provided with screw-threads 27 for pulley attachment.

The coupling of the motor spindle 6 to the motor and thence to the basket 4 can be effected in many ways, and I therefore deem it unnecessary to do more than describe such a convenient means of coupling as is shown, for instance, in the drawings,—in which a lower external internally hollow and threaded boss 28 of the motor housing 5, is extended as a hub 29 flanged at 30, into which is introduced the threaded upper portion 31 of the quill 7, and locked by the screw 32.

The operation of my extractor will be apparent to those skilled in the art. The rotation of the armature of the motor 5 and its spindle 6 effects the rotation of the basket 4, and through the intervention of my novel construction of quill and casing, with the contained buttons, friction will be reduced to a minimum, the liability of the moving parts to become unduly heated so as to stick will be eliminated, while undue or excessive vibration will be taken care of by reason of the flange 17, gasket 18 and gland 19.

The disconnecting or dismantling of the parts for the purposes of inspection or repairs can as already explained be readily effected by the removal of the fastening devices 22 and the gland 19.

In Fig. 6, instead of a rubber gasket, I employ a series of coil springs 33 located between the flange 17 and a washer 34 with which the gland 19 engages.

It will now be apparent that I have devised a novel and useful construction of a quill and housing for moisture extractor for drying clothes, which embodies the features of advantage enumerated as desirable in the statement of the invention and the above description, and while I have, in the present instance, shown and described preferred embodiments thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a moisture extractor, the combination of a casing having a concave seat there-

- in extending entirely across and closing the bottom of said casing, a quill having a convex lower portion adapted to rest upon said concave seat, a plurality of buttons having 5 convex juxtaposed faces contained within said quill, the bottom button being supported above said concave seat, a spindle supported upon said buttons, and means for retaining said bearing in position within 10 said box.
2. In a moisture extractor, the combination of a casing having a concave seat therein, a quill having a convex lower portion adapted to rest upon said concave seat, a 15 plurality of buttons having convex juxtaposed faces contained within said quill, a spindle supported upon said buttons, means for retaining said quill in position within said casing, a base member having a supporting flange thereon, a flange carried by said casing, and fastening devices for holding said flanges in assembled position.
3. In a moisture extractor, the combination of a casing having a concave seat therein, a quill having a convex lower portion adapted to rest upon said concave seat, a plurality of buttons having convex, juxtaposed faces contained within said quill, a spindle supported upon said buttons, means 25 for retaining said quill in position within said casing, comprising a flange extending laterally from said quill, a cushion composed of resilient material supported on said flange, and a gland in threaded engagement 30 with the walls of said casing for holding said cushion in position.
4. In a moisture extractor, the combination of a base member having a supporting flange, a casing having a flange secured to 40 the flange of said base member and provided with an internal concave seat, a vertical spindle bearing having a convex lower end supported within said casing and provided with a laterally extending external flange,
- 45 a cushioning device supported upon said laterally extending flange, a gland for holding said cushioning device in position, and a spindle contained within said bearing and having a button provided with a convex 50 face at its lower portion which is adapted to rest upon the convex face of a second button stepped into the lower portion of said casing.
5. A moisture extractor, which comprises 55 in combination:—a casing having a concave
- imperforate base,—a hollow quill closely fitting within said casing and supported upon said base,—a spindle revoluble within said quill,—a gasket and a gland for retaining said quill within said casing,—and means 60 for retaining said spindle in position.
6. A moisture extractor, which comprises in combination:—a hollow casing having a concave internal base,—a quill supported within said casing and axially alined therewith by means of an outward circular flange which fits within the casing,—a hollow gland encompassing the quill and threaded within the internally threaded upper walls of the casing,—a gasket surrounding the quill 70 within the casing and adapted to be compressed upon the flange of the quill by the gland,—and a revoluble spindle fitted within the hollow gland.
7. The combination in a moisture extractor, of a hollow casing having a concave internal base,—a quill supported within said casing and axially alined therewith by means of an outward circular flange which fits within the casing,—a hollow gland encompassing the quill and threaded within the internally threaded upper walls of the casing,—a gasket surrounding the quill 75 within the casing and adapted to be compressed upon the flange of the quill by the gland,—a revoluble spindle fitted within the hollow gland and externally channeled to receive lubricant,—and a means of lubricant supply.
8. The combination in a moisture extractor, of a hollow casing having a concave internal base,—a quill supported within said casing and axially alined therewith by means of an outward circular flange which fits within the casing,—a hollow gland encompassing the quill and threaded within 80 the internally threaded upper walls of the casing,—a gasket surrounding the quill within the casing and adapted to be compressed upon the flange of the quill by the gland,—a revoluble spindle fitted within the hollow gland and externally channeled to receive lubricant,—and a means of lubricant supply.
9. The combination in a moisture extractor, of a hollow casing having a concave internal base,—a quill supported within said casing and axially alined therewith by means of an outward circular flange which fits within the casing,—a hollow gland encompassing the quill and threaded within 90 the internally threaded upper walls of the casing,—a gasket surrounding the quill within the casing and adapted to be compressed upon the flange of the quill by the gland,—a revoluble spindle fitted within the hollow gland,—and a basal bearing between the lower end of the spindle and the inner end of the quill composed of convex bearing surfaces respectively connected with the spindle and the quill.

ISAAC F. WILLEY.
